BOOK END OR SIMILAR ARTICLE

Lorna T. Cardevaant, Edwardsburg, Mich.

Application March 1, 1950, Serial No. 8,242

Term of patent 3½ years

(Cl. D33—1)

To all whom it may concern:

Be it known that I, Lorna T. Cardevaant, a citizen of the United States, residing at Edwardsburg, in the county of Cass, State of Michigan, have invented a new, original, and ornamental Design for a Book End or Similar Article, of which the following is a specification, reference being had to the accompanying drawing, forming part thereof.

Fig. 1 is a front view of a book end or similar article, showing my new design.

Fig. 2 is a front perspective view of the book end or similar article, showing my new design.

The rear of the book end or similar article is plain.

I claim:

The ornamental design for a book end or similar article, as shown and described.

LORNA T. CARDEVAANT.
